UNITED STATES PATENT OFFICE.

GEORGE B. HAYES, OF DENVER, COLORADO.

CONCRETE POST.

Application filed January 15, 1925. Serial No. 2,545.

This invention relates to improvements in the construction of concrete posts.

It is well known to all that wooden posts and poles such as fence posts and telegraph and telephone poles rot at or near the ground. When the wood of a pole or post has rotted away beyond a certain amount, the pole must be replaced or the rotted end sawed off and removed and the pole reset. 10 The shortening of a telephone or telegraph pole and its resetting is a difficult job and besides the pole soon becomes too short. Fence posts are so short that if the rotted portion is removed, they become too short 15 to be employed for the same purpose and must be thrown away. It is also well known that, that part of the poles or posts that are located above the ground is always quite solid when the part underground is all decayed. It is, therefore, evident that if a 20 post or pole could be in two parts, one of concrete, which is adapted to be inserted into the ground, and a wooden portion for that part above the ground, that the poles 25 and posts would last very much longer.

It is the object of this invention to produce a concrete post that is adapted to be set into the ground and which is provided with a metal cap or bracket to which the wooden 30 post may be attached. I am aware that it is old broadly to make a post partly of concrete and partly of wood which parts are connected together by a plurality of bolts and straps. These posts are, however, 35 objectionable for several reasons which I do not think it necessary to explain.

It is an object of this invention to produce a concrete post and means for securing the wooden post in place thereon that shall 40 be simple and cheap and which is adapted to cooperate with posts of different sizes and shapes without making it necessary to cut the size of the wooden portion down to any predetermined size or to any particular 45 shape.

It is a further object to produce a device in which the wooden portion may be quickly removed or attached so as to make the operation of replacing the wooden part very 50 simple.

The above and other objects that will become apparent as the description proceeds are attained by means of a construction

which I will now describe in detail, reference for this purpose being had to the accompanying drawing in which the invention is illustrated and in which

Fig. 1 is a side elevation of the concrete part of my post, showing it in position in the ground and showing also a part of the wooden portion.

Fig. 2 is a vertical section taken on line 2-2 of Fig. 3 which is a section taken on line 3-3, Fig. 1.

Numeral 1 designates the surface of the ground and 2 the concrete portion of the post which is embedded in the ground. The part 2 is preferably cylindrical and provided with an axial opening 3 for the reception of a bolt 4. A washer 5 is embedded in the material near the lower end of the post and has the opening therein concentric with the opening 3. A cavity 6 in the end of the member 2 serves to receive the nut 7 which is held in place by a block of cement 75 or other material 8. A bracket having a base 9 and an upstanding part 10 is secured to the top of the part 2 by means of the bolt 4, in the manner clearly shown in Fig. 2. A plurality of lugs 11 project upwardly 80 from the base 9 and serve to engage the lower end of the wooden part 12 so as to space the latter from the head of the bolt 4. The upstanding part 10 has a transverse section like that shown in Fig. 3 and is formed with sides A and B which are placed at an angle to each other. These sides are connected at their bottom by a wall C that has several openings for the reception of bolts 13 that project entirely through the lower end of the part 12 in the manner shown in Fig. 2. The threaded ends of the bolts extend through the arcuate portions 14 in the manner shown in Fig. 3. By this means the lower end of the wooden post or pole can be easily and securely fastened in place. The angular relation of the sides A and B makes it possible to employ posts of

different sizes and shapes as they can readily be wedged against these sides in the manner shown in Fig. 3. Should the bracket become broken it may be removed by unscrewing the bolt 4, a new bracket may then be attached. Where small wooden posts are employed, such as are commonly used for fences, one bolt 13 may be sufficient to hold

it in place and I have therefore provided an additional opening which I have designated by the numeral 15.

It is apparent from the above that I have produced a simple and inexpensive device by means of which a wooden post may be attached to a concrete base and which makes it possible to utilize old posts that have been cut down until they are too short to be embedded in the ground. When my device is employed with new construction, the posts or poles may, of course, be cut much shorter which effects a large saving in the cost.

Although I have described my invention as employing a wooden portion above the ground, it is evident that it is as well adapted to be used in combination with a metal section instead of the wooden one. It is well known that steel or iron posts rust when inserted into the ground, and therefore it is as essential to secure these to a concrete base as it is to so secure the wooden portions.

Having now described my invention, what I claim as new is:

A concrete post comprising, in combination, an elongated member of concrete, adapted to be set into the ground, a metal bracket adapted to be secured to said member, said bracket having a base whose underside is flat and which is adapted to rest upon the upper end of said concrete member, an anchoring bolt extending longitudinally through the concrete member and through the base, the upper surface of said base having upwardly extending lugs upon which the bottom of a wooden post may rest, said base having also two angularly related sides extending upwardly, said sides having a V-shaped groove between them for the reception of round posts of any diameter and which may be held in said groove by a clamping bolt.

In testimony whereof I affix my signature.

GEORGE B. HAYES.
